Primary Examiner — Anhdao Doan(74) *Attorney, Agent, or Firm* — Meyertons, Hood, Kivlin, Kowert & Goetzel, P.C.; Eric B. Meyertons(57) **CLAIM**

The ornamental design for an x-ray marker, as shown and described.

DESCRIPTION

FIG. 1 is perspective front view of my design invention;

FIG. 2 is a front view thereof;

FIG. 3 is a top view thereof;

FIG. 4 is a side view thereof;

FIG. 5 is a bottom view thereof; and,

FIG. 6 is a back view thereof.

The broken lines in FIGS. 1 and 2 are included for the purpose of illustration a portion of the x-ray marker that forms no part of the claimed design.
